United States Patent Office.

J. HYDE FISHER, OF CHICAGO ILLINOIS.

Letters Patent No. 95,890, dated October 10, 1869; antedated April 19, 1869.

IMPROVEMENT IN NUT-LOCK.

The Schedule referred to in these Letters Patent and making part of the same.

To all whom it may concern:

Be it known that I, J. HYDE FISHER, of Chicago, in the county of Cook, and State of Illinois, have invented a useful Improvement for Fastening Nuts on Bolts; and I do hereby declare that the following is a full, clear, and exact description thereof, reference being had to the accompanying drawings, and letters marked thereon, making a part of this specification, in which—

Figure 1 is a representation of nuts secured with my improved fastener.

Figure 2, a perspective view of the back side of the washer.

Figure 3 shows the manner of countersinking the plate to fit the washer.

The nature of the present invention consists in forming projections on the back side of the washer, which fit into corresponding recesses in the iron or wood, on which the washer bears, thereby so holding the washer that when its edge or edges are turned against the nut, the latter will be held in place.

A represents a plate of iron, and B a piece of wood, on both of which my improved washer is placed, to show its adaptability to different materials.

The washer, fig. 2, is cut from any suitable material,

in the usual manner; and then, by means of a die, or other suitable tool, it is so countersunk on one side as to form small projections *d b*, which fit into corresponding depressions *d' b'*, made in the metal-plate at fig. 3.

By this means, the washer has so firm a seat that when it is turned up at its edges, as shown at E E, fig. 1, it will prevent the nut D from turning on the screw H.

When the washer has a seat on wood, or other soft material, it is not necessary to form the depressions shown at *d' b'* with a tool, as the nut D, when properly turned on, will force the depressions *d b*, fig. 2, in and hold the washer.

Having thus described my invention,

What I claim, and desire to secure by Letters Patent of the United States, is—

In combination with the nut D and screw H, a washer, C, which is so formed to have projections *d b* fitting into corresponding depressions *d' b'* in its seat, as set forth.

J. HYDE FISHER.
